[57] CLAIM

The ornamental design for a pitcher or similar article, as shown and described.

DESCRIPTION

FIG. 1 is a side elevational view of a pitcher or similar article showing my new design, the side opposite being a mirror image;

FIG. 2 is a top plan view;

FIG. 3 is a sectional view taken on line 3—3 of FIG. 2;

FIG. 4 is a bottom plan view;

FIG. 5 is a left end elevational view; and

FIG. 6 is a right end elevational view thereof.
